TURRET BOWLING PIN HOLDER

Charles E. Schalitz, 10351 Lakewood Drive,
Luna Pier, Mich. 48157

Filed Apr. 9, 1973, Ser. No. 348,931

Term of patent 14 years

Int. Cl. D21—01

U.S. Cl. D34—5 DD

FIG. 1 is a front view of a turret bowling pin holder embodying my new design;

FIG. 2 is a side view of the turret bowling pin holder illustrated in FIG. 1;

FIG. 3 is a top view of the turret bowling pin holder illustrated in FIGS. 1 and 2;

FIG. 4 is a sectional view taken along line 4—4 of FIG. 1; and

FIG. 5 is a sectional view taken along line 5—5 of FIG. 1.

I claim:

The ornamental design for a turret bowling pin holder, substantially as shown and described.
